UNITED STATES PATENT OFFICE.

CUDELLAS ARMSTRONG, OF HOBART, OKLAHOMA.

STEAM-SEPARATOR.

1,248,054.

Specification of Letters Patent. Patented Nov. 27, 1917.

Application filed July 31, 1917. Serial No. 183,799.

To all whom it may concern:

Be it known that I, CUDELLAS ARMSTRONG, a citizen of the United States, residing at Hobart, in the county of Kiowa and State of Oklahoma, have invented certain new and useful Improvements in Steam-Separators, of which the following is a specification.

This invention relates to devices for separating steam and water of the general type shown in Letters-Patent issued to me in May, 1915, so that the hot water may be returned to the boiler and the dry steam passed to the point of use. The object of the invention is to provide a novel structure by the use of which the water will be returned quickly to the boiler and the steam permitted to rise from the water and flow in a tortuous passage to the steam outlet so that it will be thoroughly dried and relieved of all moisture, drugs or sediment, thereby promoting safety in the boiler, reducing wear and increasing the efficiency of machinery, and economizing in time and fuel. A secondary object of the invention is to so construct the device that the inlet and the steam outlet will be in alinement thereby permitting the device to be very quickly and easily fitted to existing plants.

The invention is fully illustrated in the accompanying drawings, in which—

Figure 1 is a central vertical longitudinal section of an apparatus embodying my improvements;

Fig. 2 is a horizontal section of the same;

Fig. 3 is a transverse section on the line 3—3 of Fig. 1;

Fig. 4 is a similar section on the line 4—4 of Fig. 2.

In carrying out my invention, I employ a cylindrical casing or shell 1 which is provided with a water outlet 2 in one wall. The cylindrical casing or shell is provided with annular flanges 3 at its ends and to the said flanges, I secure the heads 4, said heads being of concavo convex form and one head having its convexity disposed within the cylinder. The heads are provided centrally with openings receiving threaded nozzles or collars 5, it being noted that the heads are duplicates in construction so that the cost of manufacture will be minimized and rapidity of production assured. The head having its convexity within the cylindrical casing or shell is disposed at the inlet end of the shell and an inlet pipe 6 is fitted in the collar 5 in said head and has its inner end turned down-

wardly and disposed approximately over the water outlet 2, as clearly shown in Fig. 1. Disposed longitudinally within the shell, on the opposite sides of the same and slightly above the inlet pipe 6, are cleats or baffles 7 which serve as supports for a bridge 8 consisting of a plate of metal having perforations 9 formed therethrough. The said perforations permit the steam to rise through the bridge and the baffles serve to deflect the steam at the sides of the shell toward the center thereof so that it will be deflected from a straight upward path and thereby retained in the water space or the space below the bridge for a short period to assist in heating the bridge which will react upon the steam to partially dry the same. The inner edge of the bridge 8 is disposed against a vertical partition or baffle 10 which extends across the shell 1 and has its lower edge secured to or formed integral with a bottom plate 11 which extends to the outlet head 4 of the device. This bottom plate 11 rests upon cleats or baffles 12 disposed longitudinally within the shell, the partition 10 and bottom plate 11 constituting a baffle cage which may be slid through the end of the shell and rested upon the cleats 12 before the outlet head 4 is secured in place. Perforations 13 are provided in the upper portion of the partition 10 to permit the steam to pass into the baffle cage and one or more drip nozzles 14 are provided in the bottom plate 11 near the outlet head 4 to permit the water of condensation to drain back into the water space of the casing. Within the baffle cage, I provide a plurality of vertical baffles 15 which are disposed in staggered relation, as shown most clearly in Fig. 2, and have concave or V-shaped faces presented toward the partition 10 to be acted upon by the incoming steam. The steam striking these baffles will be diverted and will circulate in a tortuous manner around the several baffles and will finally escape through the outlet collar 5, as will be readily understood. As the steam strikes the baffles 15 the moisture contained therein will be arrested and will trickle down the said baffles to the bottom plate 11 and will eventually escape through the perforations 14. As the operation of the device continues, the baffles will become heated and will then react upon the steam so as to dry the same and relieve it of all moisture, the steam escaping through the outlet being generally free of all moisture and

- super-heated so that it will very quickly perform the work allotted to it. To hold the steam to the baffles 15 an arched deflector 16 is secured to and projects from the partition 5 over the upper ends of the baffles and in spaced relation to the shell 1, the space between the said arch and the shell serving to prevent loss of heat through radiation from the shell. On the inner side of the partition 10 below the bridge 8, I provide a transverse baffle or deflector 17 which serves to turn downwardly the water which may tend to rise with the steam from the end of the inlet pipe 6.
- 15 It will be readily noted that the inlet and the steam outlet in my present device are in axial alinement so that the apparatus may be readily interposed in and fitted to any plant now in use. By arranging the discharge end of the inlet pipe or elbow 6 approximately over the water outlet 2 the hot water is returned quickly to the boiler while the steam will rise from the water immediately upon the issuance of the mixed 20 steam and water from the said elbow. The steam cannot pass directly to the steam outlet but must rise through the bridge 8 and then pass through the upper portion of the partition 10 so that these elements will be 25 raised in temperature and will react so as to dry the steam. The partition 8 and the baffle cage need not be secured to the cleats upon which they rest, but may simply rest loosely thereon and will be held against rising 30 by the cylindrical contour of the casing. They may, consequently, be easily slid into or removed from the casing so that repairs or renewals may be very conveniently 35 made.
- 40 Having thus described the invention, what is claimed as new is:
1. In a steam separator, the combination of a casing having an inlet in one end, a steam outlet in its opposite end and a water 45 outlet in its lower side, a bridge above the inlet, and a baffle cage bearing against the inner edge of said bridge and disposed above the lower side of the shell and separating the inlet from the steam outlet.
  - 50 2. In a steam separator, the combination of a casing having an inlet in one end and a steam outlet in the opposite end, a bridge disposed within the casing at one end thereof above the inlet, a baffle cage supported within the casing above the lower side 55 thereof and having a vertical partition bearing against the said bridge, the bridge and the said partition being provided with perforations, and a plurality of baffles within the baffle cage.
3. In a steam separator, the combination of a casing having an inlet at one end and a steam outlet at the opposite end, a bridge disposed across the casing at the inlet end of the same and above the inlet, a baffle cage 60 supported within the casing and comprising a vertical partition abutting the inner end of the said bridge, and a bottom plate extending from the said partition to the outlet end of the casing in spaced relation to 70 the lower side of the casing, the said bridge, partition and bottom plate being perforated, a plurality of baffles within the baffle cage, and a baffle on the inner face of the partition below the bridge.
4. A steam separator comprising a casing having an inlet in one end, a steam outlet in its opposite end and a water outlet in its lower side, an inlet pipe secured in the inlet of the casing and having its inner end 80 turned downwardly approximately over the water outlet, a bridge disposed across the inlet end of the casing and above the inlet, said bridge being perforated, a vertical partition disposed within the casing and 85 abutting the bridge, the upper portion of said partition being perforated, a bottom plate extending from the said partition to the outlet end of the casing in spaced relation to the lower side of the casing and being perforated adjacent the outlet end thereof, a baffle on the inner face of the partition below the bridge, a plurality of vertically disposed baffles rising from the said bottom plate in staggered relation and 90 having concave faces presented toward the vertical partition, and an arch extending over the upper ends of the baffles in spaced relation to the casing.
5. In testimony whereof I affix my signature. 100
- CUDELLAS ARMSTRONG. [L.S.]
